Attorney.

UNITED STATES PATENT OFFICE.

FRANK WINCHELL, OF WATERLOO, IOWA.

HYDROCARBON-HEATER FOR CARBURETERS.

1,308,135.

Specification of Letters Patent.

Patented July 1, 1919.

Application filed September 21, 1917. Serial No. 192,594.

To all whom it may concern:

Be it known that I, FRANK WINCHELL, a citizen of the United States of America, and a resident of Waterloo, Blackhawk county, 5 Iowa, have invented certain new and useful Improvements in Hydrocarbon-Heaters for Carbureters, of which the following is a specification.

My invention relates to improvements in 10 hydrocarbon heaters for carbureters, and the object of my improvement is to provide for a carbureter an attachment or auxiliary heating means for heating kerosene or any other relatively slowly vaporizing hydro- 15 carbon previous to its deposition in the carbureter to insure its constant vaporization therein.

This object I have accomplished by the means which are hereinafter described and 20 claimed, and which are illustrated in the accompanying drawings, in which the figure is a diagrammatic elevation, in partial longitudinal section, of my improved hydrocarbon heater as operatively connected to a carbureter.

The carbureter 11 may be of any type, the one shown being a float-valve controlled one as ordinarily employed in association with an internal-combustion motor, and having a 25 delivery-pipe 12 in communication with the manifold 13 of such a motor not shown.

The numeral 14 denotes a valve-chamber whose valve is controlled by a hand-wheel 16, and receives a supply of light easily 30 vaporized hydrocarbon, such as gasolene, by way of a pipe 17 leading to a reservoir, not shown, the valve chamber having a delivery-nipple 15 mounted within the manifold 13, and provided with a plurality of small ori- 35 fices to spray the gasolene in small streams to insure its instantaneous vaporization.

My improved heating attachment is adapted for connection to the carbureter to deliver kerosene or other relatively heavy hydrocarbon thereinto in a suitably heated state, from a reservoir 1.

A tube 2, which may be of coupled sections as shown, leads from the reservoir 1 into the carbureter 11.

50 The numerals 4 and 5 denote sections of a pipe placed in communication by means of a T-coupling 3, and serving as a conduit for the exhaust gases of the motor. The section 5 of said pipe has a rock-valve 6 mounted therein, operated manually by means of a

crank-handle 7, or by any other desired means, to variably restrict the passage of gases therethrough.

The numeral 8 denotes a section of pipe inclosing a part of the tube 2, said tube 2 being passed through the T-coupling 3 and centrally through the pipe 8. One end of the pipe 8 is threaded into said T-coupling 3, the other end being threaded into an elbow-coupling 9, the latter delivering into 65 a branch exhaust-pipe 10, and the tube 2 passes through said elbow 9 to a connection with said carbureter 11.

The motor is started by injection of gasolene in a spray into the manifold 13 through 70 the small orifices of the nipple 15. Exhaust-gases, in a highly heated state, in passing through the exhaust-pipe 4—5, are partially deflected to pass through the pipe 8 and branch exhaust-pipe 10, by means of the baf- 75 fling action of the valve 6, which latter may be rocked to variably restrict the passage in the pipe-section 5, as may be necessary under varying degrees of temperature of the atmosphere. The gases passing through the 80 pipe 8 heat the hydrocarbon flowing through the tube 2 previous to its delivery into the carbureter, where the hydrocarbon is received at a temperature insuring its immediate vaporization, which condition is con- 85 stantly maintained as long as the motor is in operation, or while heated gases are deflected into the pipe 8 by the baffling action of the valve 6.

My improved heating attachment is sim- 90 ple and easily assembled, as also quickly disassembled for the purpose of cleaning or carriage, and may be connected to any kind of carbureter.

Having described my invention, what I 95 claim as new, and desire to secure by Letters Patent, is:

In combination, a tank, a conduit in communication with said tank, a pipe for carrying a heated fluid under head and traversed 100 transversely by said conduit, a throttle-valve in said pipe located beyond the place of traversing of said conduit, and a by-pass in communication with said pipe at the location of its traversing by said conduit, the conduit 105 being carried through a part of said by-pass interiorly in spaced relation thereto.

Signed at Waterloo, Iowa, this 5th day of Sept., 1917.

FRANK WINCHELL
